US0D1065860S

(12) **United States Design Patent** (10) **Patent No.:** **US D1,065,860 S**
(45) **Date of Patent:** **** Mar. 11, 2025**

(54) **SMART TOILET PAPER DISPENSER
DRAWERS**

(71) Applicant: **Smart TP**, San Jose, CA (US)

(72) Inventor: **Masiullah Razai**, San Jose, CA (US)

(73) Assignee: **Smart TP**, San Jose, CA (US)

(**) Term: **15 Years**

(21) Appl. No.: **29/882,476**

(22) Filed: **Jan. 14, 2023**

(51) LOC (15) Cl. **23-08**

(52) U.S. Cl.

USPC **D6/522**

(58) **Field of Classification Search**

(57) **CLAIM**

The ornamental design for smart toilet paper dispenser drawers as shown and described.

DESCRIPTION

FIG. 1 is a front perspective view of smart toilet paper dispenser drawers showing my new design.

FIG. 2 is a front view thereof.

FIG. 3 is a left side view thereof.

FIG. 4 is a right side view thereof.

FIG. 5 is a top view thereof.

FIG. 6 is a bottom view thereof; and,

FIG. 7 is a back view thereof.

The broken lines depict environment and portions of the article that form no part of the claimed design. FIGS. 1-4 and 7 are shown in an environment of use. FIGS. 5 and 6 are shown without environment.

1 Claim, 7 Drawing Sheets
